(57) **CLAIM**

The ornamental design for wire crate with blow molded base, as shown and described.

DESCRIPTION

FIG. 1 is a top rear perspective view of a first embodiment of a wire crate with blow molded base in accordance with our new design;

FIG. 2 is a top front perspective thereof;
FIG. 3 is a bottom rear perspective thereof;
FIG. 4 is a bottom front perspective thereof;
FIG. 5 is a front elevational view thereof;
FIG. 6 is a rear elevational view thereof;
FIG. 7 is a right side elevational view thereof;
FIG. 8 is a left side elevational view thereof;
FIG. 9 is a top view thereof;
FIG. 10 is a bottom view thereof;
FIG. 11 is a partial cross-section view taken along line 11-11 in FIG. 10;
FIG. 12 is a partial cross-section view taken along line 12-12 in FIG. 10;
FIG. 13 is a top rear perspective view of a second embodiment of a wire crate with blow molded base;
FIG. 14 is a top front perspective of FIG. 13;
FIG. 15 is a bottom rear perspective of FIG. 13;
FIG. 16 is a bottom front perspective of FIG. 13;
FIG. 17 is a front elevational view of FIG. 13;
FIG. 18 is a rear elevational view of FIG. 13;
FIG. 19 is a right side elevational view of FIG. 13;
FIG. 20 is a left side elevational view of FIG. 13;
FIG. 21 is a top view of FIG. 13;
FIG. 22 is a bottom view of FIG. 13;
FIG. 23 is a partial cross-section view taken along line 23-23 in FIG. 22; and,
FIG. 24 is a partial cross-section view taken along line 24-24 in FIG. 22.

The broken lines forming a rectangle in FIGS. 2, 4, 5, 14, 16, and 17 are boundary lines and are for illustrative purposes only and form no part of the claimed design. The dashed lines in FIGS. 11, 12, 23, and 24 are section lines and are for illustrative purposes only and form no part of the claimed design. The double dash-dot-dash lines at each corner of FIGS. 1-8 and 13-20 are for illustrative purposes only and form no part of the claimed design. The dashed lines on the top of the base in FIGS. 1, 2, 9, 13, 14, and 21 are for illustrative purposes only and form no part of the claimed design.
